Primary Examiner—Stella Reid*Assistant Examiner*—Doris V. Coles*Attorney, Agent, or Firm*—Arthur L. Liberman[57] **CLAIM**

The ornamental design for a tester for insect attractancy and repellency, as shown and described.

DESCRIPTION

FIG. 1 is a perspective view of a tester for insect attractancy and repellency, showing our new design;

FIG. 2 is a front elevational view with part of the top central pipe cut away for the convenience of illustration, the rear being a mirror image thereof;

FIG. 3 is a top plan view;

FIG. 4 is a bottom plan view;

FIG. 5 is a front elevational view of a second embodiment, with part of the top central pipe cut away for the convenience of illustration, the rear being a mirror image thereof;

FIG. 6 is a top plan view; and,

FIG. 7 is a bottom plan view.
